[57] CLAIM

The ornamental design for a cup or similar article, as
shown and described.

DESCRIPTION

FIG. 1 is a side elevational view of a tea cup or similar
article showing my new design, the opposite side view
being a mirror image thereof;

FIG. 2 is a top plan view thereof;

FIG. 3 is a bottom plan view thereof;

FIG. 4 is a sectional view thereof taken along line 4—4
of FIG. 2;

FIG. 5 is a front elevational view thereof; and

FIG. 6 is a rear elevational view thereof.
